PIVOTABLE POLE-TYPE LOAD LIFTING
APPARATUS
Theodore W. Tuschen, Sun Prairie, Wis.
Filed Jan. 15, 1965, Ser. No. 425,889
3 Claims. (Cl. 27—27)

This invention relates to load lifters and more particularly to body and casket lifting apparatus.

While the lifting apparatus shown in the drawings is designed for lifting bodies and caskets in such usually confined quarters as the preparation rooms in a mortuary, my invention finds particular advantageous employment wherever relatively heavy loads must be handled in cramped working areas.

Known body and casket lifters generally have a wheel-mounted base supporting an upright standard and have a lifting boom attached to the standard and extending outwardly over the wheel-mounted base. For handling such heavy and bulky objects as caskets, the bases of this type of lifter must be quite large to prevent the apparatus from tipping over and, therefore, they have been found to be very cumbersome to use, especially in rather small preparation rooms common in mortuaries. It has also been found that the wheel-mounted base, which must necessarily extend outward under the load lifting boom to prevent the apparatus from being tipped over by the load, often prevents the lifter from being moved in sufficiently close to a bier to allow a casket to be properly lowered onto the bier. The large wheel-mounted bases likewise interfere with the lowering of a body into a casket and with the lifting of a casket out of a shipping crate.

Accordingly, it is an object of my invention to provide a new and improved load lifting apparatus.

Another object of my invention is to provide a floor-to-ceiling, pole-type, body and casket lifter which has a 360° working arc.

Another object of my invention is to provide a floor-to-ceiling, pole-type, body and casket lifter which can be readily set up and taken down.

A still further object of my invention is to provide a sturdy, light-weight, body and casket lifter which has a dignified and professional appearance.

Further objects, features and advantages of my invention will be apparent from the following detailed description taken in conjunction with the accompanying drawings showing a preferred exemplary embodiment of my invention.

In the drawings:

FIG. 1 is a perspective view of a preferred form of my invention supporting a casket,

FIG. 2 is an enlarged fragmentary side view of the upper end of the upright standard of my invention with portions broken away to show attachment to an upper supporting surface.

FIG. 3 is an enlarged fragmentary cross section view taken along line 3—3 of FIG. 1 showing a portion of the upright standard of my invention.

Referring now more specifically to the drawings, in FIG. 1, a load lifter 10 comprising my invention is shown supporting a casket 11. Generally, lifter 10 has an adjustable, floor-to-ceiling, pivotable standard 12 comprising a lower tubular section 13 and an upper tubular section 14 which telescopes into the lower section 13, a boom 15 and a jack 16 for raising and lowering the boom 15. The standard 12 has top and bottom swivel pins 17 and 18, respectively, which are pivotably carried in ceiling and base swivel plates 19 and 20, respectively. The standard 12 is adapted to be rotated 360 degrees in swivel plates 19 and 20.

The upper swivel pin 17 and the upper or ceiling swivel

2

plate 19 are shown in detail in FIG. 2. The upper swivel pin 17 is mounted on the upper end of tubular standard section 14 by a plug 21 having a neck portion 21a adapted to be frictionally held in tubular section 14 and a flange portion 21b adapted to abut the end of the tubular section 14. The pin 17, which may be made of steel, nylon, or other satisfactory material, may be fixedly secured in plug 21 by welding or other suitable means. The pin 17 is adapted to be pivotably received in a recess 19a in upper swivel plate 19. Swivel plate 19 has a plurality of holes 22 adapted to receive screws 23 for fixedly attaching it to a ceiling or other supporting surface such as 24 shown in FIG. 2.

The lower end of the standard 12 is substantially identical to the upper end except, of course, the base plug 25 is slightly larger than the upper plug 21 to facilitate its insertion into the lower tubular standard section 13 which has a slightly larger inside diameter than the upper tubular section 14. The base swivel plate 20 need not be fixedly attached to the floor or other lower supporting surface since it will be maintained in position by the weight of the lifter and the load. For a more permanent installation, instead of using a bottom swivel plate such as 20, a small cup or socket may be recessed in the floor or other lower supporting surface for receiving the lower swivel pin 18.

As shown in FIG. 1, a boom 15 is pivotally mounted on the lower tubular standard section 13 for movement about a horizontal pivot pin 26. In a preferred form 30 boom 15 comprises a pair of steel arms 27 and 28 joined at their rear ends by pivot pin 26 which is carried in boom mounting bracket 29 which is fixedly secured to the upper end of lower standard section 13 by welding or other suitable means. The forward end of boom arms 35 27 and 28 are joined by a carrier pin 30. Boom 15 supports suitable load carrying means, shown in the drawings in the form of an elongated suspension bar 31 having a plurality of slings 32 attached thereto. This type of load carrying means which is particularly adapted for handling a body or a casket such as shown at 11 is well known and forms no part of my invention.

The boom 15 is adapted to be pivoted between upper and lower positions by a conventional hydraulic jack 16 comprising a cylinder 33 and a piston 34. The piston 34 45 as shown in its extended position in FIG. 1, is pivotably attached to boom arms 27 and 28 intermediate their forward and rear ends by pin 35. Cylinder 33 has a base portion 36 which is pivotably attached to a mounting bracket 37 by pin 38. Bracket 37 is secured to the lower tubular standard section 13 by any suitable means such as welding. Jack 16 has an operating lever 39 which is adapted to operate the jack in the conventional manner.

Referring now to FIGS. 1 and 3, the upper tubular standard section 14 is telescoped into the lower standard section 13. The lower standard section 13 has a plurality of vertically spaced pairs of adjusting holes 40. An adjusting pin 41 may be inserted into a selected pair of holes 40 for varying the height of the standard 12. Locking means are provided in the form of key 42 which is received in transverse hole 43 in adjusting pin 41 for positively retaining adjusting pin 41 in the selected pair of adjusting holes. The upper standard section 14 is resiliently supported in the lower section 13 by a coil spring 44 which rests on adjusting pin 41.

To erect the load lifter 10 the adjusting pin 41 is positioned in a pair of adjusting holes 40 which will make the height of the standard 12, when the coil spring 44 is substantially uncompressed, slightly greater than the height of the ceiling. The upper swivel pin 17 is then inserted into the recess 19a in swivel plate 19 which is attached to the ceiling and the standard is manually com-

pressed to a height less than the ceiling height of the room by exerting a compression force on the coil spring by telescoping the standard sections together. The lower swivel pin 18 is then inserted into base swivel plate 20 and the coil spring 44 is allowed to extend the standard and maintain the swivel pins in their respective swivel plates.

It is readily apparent that my load lifter requires only a very small amount of floor space and that there are no obstructions at the base extending outwardly under the lifting boom which would interfere with the moving of bodies to and from preparation tables and caskets or which would hinder the movement of caskets to and from shipping crates, biers, or the like.

It is further apparent that my load lifter has a 360° 15 working arc and can be freely swivelled about its vertical axis.

It is understood that my invention is not confined to the particular construction and arrangement of parts herein illustrated and described, but embraces all such modified forms thereof as come within the scope of the following claims.

I claim:

1. Body and casket lifting apparatus comprising:
  - (a) an adjustable upright floor-to-ceiling standard having axially aligned telescoping upper and lower tubular sections, 25
  - (b) said lower tubular section having a downwardly disposed smooth swivel pin mounted at its lower end and said upper section having an upwardly disposed smooth swivel pin mounted at its upper end, 30
  - (c) an upper member adapted to be secured to an upper supporting surface and having a downwardly opening recess therein for receiving said upwardly disposed swivel pin, 35
  - (d) a base member adapted to be located on a lower supporting surface and having an upwardly opening recess therein for receiving said downwardly disposed swivel pin,
  - (e) said upright standard being adapted to rotate 360° 40 on said swivel pins,
  - (f) a lifting boom pivotably mounted on the lower section of said standard for movement about a horizontal axis,
  - (g) means for raising and lowering said boom.

2. Body and casket lifting apparatus as specified in claim 1 including a coil spring adjustably mounted in said lower tubular section for resiliently supporting said upper tubular section therein.

3. Body and casket lifting apparatus comprising:

- (a) an upright standard having a lower tubular section and an upper tubular section adapted to telescope into said lower tubular section,
- (b) said lower tubular section having a downwardly disposed smooth swivel pin at its lower end and said upper tubular section having an upwardly disposed smooth swivel pin at its upper end,
- (c) an upper member adapted to be secured to an upper supporting surface and having a downwardly opening recess therein for receiving said upwardly disposed swivel pin,
- (d) a base member adapted to be located on a lower supporting surface and having an upwardly opening recess therein for receiving the downwardly disposed swivel pin of said lower tubular section,
- (e) said upright standard being adapted to rotate 360° on said swivel pins,
- (f) a coil spring adjustably mounted in said lower tubular section for resiliently supporting said upper tubular section in said lower tubular section,
- (g) a lifting boom having forward and rear ends, the rear end of said lifting boom being pivotably pinned to said lower tubular section for movement about a horizontal axis, and
- (h) a hydraulic jack for raising and lowering said boom, said jack comprising a cylinder pivotably mounted on the lower tubular section of said upright standard and a piston pivotably attached to said lifting boom intermediate its forward and rear ends, said jack having an operating lever.
